UNITED STATES PATENT OFFICE.

JOSEPH C. CRAMP, OF PHILADELPHIA, PENNSYLVANIA.

PORTABLE RAMMER.

SPECIFICATION forming part of Letters Patent No. 624,458, dated May 9, 1899.

Application filed May 12, 1898. Serial No. 680,467. (No model.)

To all whom it may concern:

Be it known that I, JOSEPH C. CRAMP, a citizen of the United States, residing at No. 1344 Eyre street, in the city of Philadelphia, in the 5 county of Philadelphia and State of Pennsylvania, have invented a new and useful Machine which I term a Portable Rammer, of which the following is a specification.

Under the existing process of preparing 10 molds for castings in foundry-work the sand or earth of which the mold is composed is packed or "rammed up," as the operation is called, by hand labor. To prevent the molten metal from spreading beyond the desired limits of the mold or "straining" when 15 it is poured into the mold, it is essential that the mold should be both closely and uniformly rammed. In ramming by hand there is a wide variation in the force of the 20 blows delivered, and in consequence some layers or portions of the mold will be closely and some loosely rammed. When the metal is poured into the mold, the loosely-rammed portions yield under the pressure and the 25 casting alters its proper shape or "strains." This necessitates the subsequent turning off of the superfluous metal at a loss of time, labor, and material.

The object of my invention is to perform 30 the operation of ramming up molds for casting and similar work by means of a portable rammer, operated by steam or compressed air, suitably suspended over the molding-pit and directed by hand. To accomplish this 35 object, my invention involves the features of construction and combination or arrangement of devices hereinafter described and claimed, reference being made to the accompanying drawings, in which—

40 Figure 1 is a vertical section of the portable rammer exclusive of the rods joining the two cylinders. Fig. 2 is a detail view, in side elevation, of the trip which governs the valve. Fig. 3 is a view in side elevation of the 45 entire portable rammer exclusive of the flexible supply-pipe and its connections. Fig. 4 is a view of the means for suspending the rammer.

In Fig. 1, A A' are inverted cylinders, disposed vertically one above the other, in which 50 the piston-rod B operates by means of the trunk-pistons C C'. D D' are exhaust-ports in the sides of the cylinders A A'. T T' are

steam-ports in the sides of the trunk-pistons C C'. F is a branch pipe communicating with the cylinders A A'. G is an ordinary 55 three-way or Corliss valve communicating with the branch pipe F. Communicating with the valve G is the pipe J, to which is detachably coupled the flexible pipe V, as shown at U, for conveying steam or compressed air 60 to the cylinders of the rammer. The trip I, attached to the piston-rod B, engages the lever H of the valve G, and thereby operates automatically the three-way or Corliss valve G. This trip I is shown in detail in side elevation at Fig. 2. The rammer E is attached to 65 the lower end of the piston-rod B.

In Fig. 3 the rods K K' K" are shown which connect the cylinders A A'. S S are handles attached to the sides of the cylinder A'. L is 70 a ring attached to the upper end of the cylinder A.

The operation of the portable rammer is as follows: Steam or compressed air being supplied through the flexible hose or pipe V, Fig. 1, is alternately admitted by the valve G to the cylinders A and A', Fig. 1. At the instant that the trunk-piston rises and the steam or air exhausts through the steam-port D the valve G cuts off from the cylinder A and opens to 80 the cylinder A'. The trunk-piston C' then descends and exhausts in a similar manner through the steam-port D'. The trip I, rising and falling with the stroke of the piston-rod B, engages the end of the lever H, which in 85 turn automatically opens and closes the valve G, admitting steam or air alternately to the cylinders A and A'. The piston-rod B, with its rammer E, thus rises and falls with a stroke uniform in rapidity and force. The rapidity 90 of the blows can be increased by increasing the pressure of the steam or air. A workman stands in the molding-pit and directs the blows of the rammer by means of the handles S S, Fig. 3, which are attached to the 95 sides of the cylinder A' at a convenient height. The apparatus is flexibly suspended by means of suitable devices for that purpose, the ring L supplying the means for such connection.

Any flexible means for suspending the rammer may be employed, such as a rope passing around a pulley secured to a ceiling-plate, as indicated in Fig. 4, in which W is the ceiling-plate, X the pulley, Y the rope, and L

the ring or strap attached to the upper end of the cylinder A of the suspended rammer.

What I claim as my invention, and desire to secure by Letters Patent, is—

5. 1. In combination, in a power-operated ramming device, an upper and a lower cylinder rigidly connected, a piston-rod with upper and lower pistons working in said upper and lower cylinders, a rammer attached to the lower end of said piston-rod, a valve automatically governed by the piston-rod and admitting power alternately to said upper and lower pistons, a flexible pipe communicating with said valve, means such as the handles 15 S S for guiding and directing the operation of said ramming device, and means for flexibly suspending said ramming device, substantially as described.
2. In combination, an inverted upper and 20 lower cylinder rigidly connected, a piston-rod with upper and lower single-acting piston-heads working vertically in said upper and lower cylinders, a rammer attached to the lower end of said piston-rod, and valved connections for supplying power alternately to said upper and lower piston-heads, controlled by the piston-rod; means for flexibly suspending said device, and means such as handles 25 S S for conveniently directing the vertical 30 position of the same, substantially as described.
3. In combination, forming a power-oper-

ated ramming device, a piston-rod working vertically in an upper and a lower cylinder, devices rigidly connecting said cylinders, a rammer attached to the lower end of said piston-rod, a branch pipe communicating with said upper and lower cylinders, a valve mounted in and controlling said branch pipe, a lever attached to said valve, a trip attached to said piston-rod and adapted to actuate the valve, and a flexible pipe communicating with said valve, substantially as described and for the purposes set forth. 35

4. In combination, an inverted lower cylinder, an inverted upper cylinder arranged vertically above said lower cylinder and rigidly connected therewith, a piston-rod and trunk-pistons operating vertically in said cylinders, a rammer attached to the lower end of said 40 piston-rod, a branch pipe communicating with said upper and lower cylinders, a valve communicating with said branch pipe, a lever attached to said valve, a trip attached to said piston-rod between said upper and lower 45 cylinders engaging said lever, and a flexible pipe communicating with said valve, substantially as described and for the purposes set forth. 50
